T. TOMMASINA.
TELEPHONIC RECEIVER FOR WIRELESS SIGNAL APPARATUS.

(Application filed May 24, 1900.)

(No Model.)

UNITED STATES PATENT OFFICE.

THOMAS TOMMASINA, OF GENEVA, SWITZERLAND, ASSIGNOR TO PAUL GALOPIN, OF GENEVA, SWITZERLAND.

TELEPHONIC RECEIVER FOR WIRELESS SIGNAL APPARATUS.

SPECIFICATION forming part of Letters Patent No. 700,161, dated May 13, 1902.

Application filed May 24, 1900. Serial No. 17,788. (No model.)

To all whom it may concern:

Be it known that I, THOMAS TOMMASINA, of Geneva, Switzerland, have invented an Improved Telephonic Receiver for Wireless Signal Apparatus, of which the following is a specification.

My invention relates to a telephonic receiver for wireless signal apparatus for Hertzian rays, which may be called a "coherer-telephone," and in carrying out my invention I employ a telephone-receiver and provide the diaphragm thereof with a coherer which is connected electrically to suitable terminals on the receiver, said terminals being connected, respectively, to the air-line and ground; and which also act as terminals for a relay-circuit, the latter circuit controlling a second circuit in which the electromagnet of the telephone-receiver and a recording apparatus are connected, so that the relay-circuit is closed through the coherer by the Hertzian rays passing through the same from the air-line to ground, and the said second circuit is closed in turn by the relay to operate the recording apparatus and energize the magnet to operate the receiver-diaphragm, producing a sound and at the same time discohering the cohering material of the coherer. The sound produced by the receiving instrument is sufficiently 30 loud to be heard distinctly without placing the instrument to the ear; and hence in use it is not necessary to remove the instrument from its hook or other similar means of support.

35 The accompanying drawings show, by way of example, one construction of the instrument.

Figure 1 is an axial section of the same with diagrammatical indication of the electrical circuit. Fig. 2 is an under side view of Fig. 1. Fig. 3 shows in section another form of membrane.

For better understanding of the drawings the thickness of the parts forming the membranes is exaggerated.

45 *a* is the electromagnet, the binding-posts *r* and *s* of which are connected in a circuit comprising a battery, a relay, and any suitable registering apparatus 3—for instance, a Morse receiver.

50 *b* is the iron diaphragm of the ordinary tele-

phonic receiver, one face of which is covered with a sheet of insulating material *c*, such as paper, on which is fixed, by means of a second sheet of insulating material *d*, a plate of 55 insulating material *e*, having an opening *f*, forming the recess in which the cohering powder (metallic filings, carbon powder, &c.) is lodged.

g is a sheet of mica closing the recess, allowing the cohering powder, however, to be observed.

h and *i* are two metallic conductors, preferably made of silver and which form the electrodes intended to be temporarily connected by the cohering powder when acted upon by the Hertzian rays.

It will be easily understood that on the one hand the Hertzian rays acting upon the aerial conductor and by means of the same upon the circuit formed by the conductors *h* and *i* close the circuit by their cohering action upon the cohering powder and act upon the signal-registering apparatus by means of the relay 2, which closes the circuit of the battery 1, 70 and at the same time the current sent through the electromagnet *a* produces the rising and falling of the membrane, from which results the necessary mechanical shaking to disperse the cohering powder.

80 In the form represented in Fig. 3 the membrane *k* is made of insulating material and carries an iron plate *l*, fixed by means of a paper covering *f'* and intended to work as the armature of the electromagnet *e*. In the 85 membrane itself is formed a cavity *m*, containing the cohering powder and in which the electrodes *n* and *o* (which in this case are formed of two sheets of silver connected to the wires *h* and *i*) terminate.

90 *p* and *q* are sheets of mica closing the cavity.

The case of the electromagnet is generally made of iron not magnetized. The space between the electrodes and the electromagnet must be greater than five millimeters if it be 95 desired to have a loud sound and a little less if a weaker sound is sufficient. Besides, the distance depends on the power of the current of the battery 1 and on the size of the electromagnet and also on the sensibility of the 100 apparatus.

The characteristic feature of my invention

is that the coherer is fixed to the vibrating membrane of a telephone-receiver. With this quite new construction one may practically obtain by merely exchanging the cohering powder and without changing any other portion of the apparatus two different results, as follows:

First. If the cohering powder supplied in the apparatus is made of non-magnetic metal 10 or of a combination of non-magnetic metals, as gold, silver, platinum, or the like, the receiver will be very sensitive and be liable to be acted upon at great distance. The same will then be connected with a relay 2, and the 15 signals will be transmitted to a recording apparatus 3, as shown in the drawings.

Second. If the cohering powder supplied in the apparatus is made of magnetic metal or of a combination of magnetic metals, (nickel, 20 cobalt, iron, steel,) the receiver will be somewhat less sensitive, but it will work with more precision because of the magnetic action of the electromagnet upon the cohering powder, which magnetic action aids the mechanical 25 shaking action of the said electromagnet for discohering the cohering powder. This double discohering action prevents any error in the transmission of signals. The apparatus will again be connected with a relay 2 and 30 the signals be transmitted to a recording apparatus 3, as shown in the drawings.

The cavity containing the cohering powder may be in the center of the membrane or concentric to it, and it may be of regular section, 35 square, or rectangular of suitable dimensions.

The electrodes in contact with the cohering powder may be of plain metallic wires or of thin blades of silver or other metal forming continuation of the wires or fixed side by side 40 of the disk, leaving between each a fraction of a millimeter. This distance also must vary according to the sensitiveness that is given to the apparatus. The larger this distance is the less sensitive the apparatus will be, 45 whatever may be the form or the substance of the electrodes in contact with the cohering powder. Similarly the size and quantity of said cohering powder, and consequently the size of the cavity, is inversely as the sensitiveness. Both conductor-wires terminate at 50 two binding-posts laterally to the cover of the telephone, to which are connected the two

ends of the circuits of the battery *t*, containing the relay 2. This relay is intended to close the circuit of the electromagnet *a*, in which are inserted the battery 1 and the recording apparatus 3. The aerial wire *u* and the earth-wire *v* are also connected with the ends of the same contacts *h* and *i*.

I claim as my invention—

1. In a telephonic signal-receiving apparatus for Hertzian rays, the combination with the electromagnet employed therein, of an armature, a disk of insulating material connected to but insulated from said armature 65 and having a recess therein, cohering powder retained in said recess, electrical conductors in contact with said cohering powder and binding-posts to which their ends are connected, an electric circuit with terminals connected to the electromagnet, a relay and an electric circuit in which the relay is embraced 70 with terminals connected to the binding-posts, and an aerial line and a line to ground also connected to said binding-posts substantially 75 as and for the purposes specified.

2. In a telephonic signal-receiving apparatus for Hertzian rays, the combination with the electromagnet employed therein, of a movable diaphragm comprising the armature 80 of the electromagnet, a disk of insulating material provided with a centrally-placed recess and connected to and insulated from the said diaphragm, metallic cohering powder placed within said recess and means for retaining 85 the same therein, electrical conductors in contact with said cohering powder, binding-posts to which the ends of said conductors are secured, an aerial wire connected to one binding-post and a ground connection to the other 90 binding-post, a battery, a relay, and electrical connections comprising a circuit whose terminals are said binding-posts, a battery and a recorder in circuit with the electric magnet and which circuit is closed by said relay, substantially as and for the purpose set forth.

In testimony that I claim the foregoing as my invention I have signed my name in presence of two subscribing witnesses.

THOMAS TOMMASINA. [L. S.]
